UNITED STATES PATENT OFFICE.

WILLIAM NELESEN, OF SHEBOYGAN, WISCONSIN.

MACHINE FOR COLLECTING WASTE METAL ARTICLES.

1,416,860.

Specification of Letters Patent. Patented May 23, 1922.

Application filed June 15, 1920. Serial No. 389,103.

To all whom it may concern:

Be it known that I, WILLIAM NELESEN, a citizen of the United States, and resident of Sheboygan, in the county of Sheboygan and

5 State of Wisconsin, have invented certain new and useful Improvements in Machines for Collecting Waste Metal Articles; and I do hereby declare that the following is a full, clear, and exact description thereof.

10 My invention relates to new and useful improvements in machines for collecting small articles of metal such as nuts, bolts, screws, tacks and small pieces of scrap metal.

15 At the present time in most manufacturing plants there is a considerable wastage of small articles of metal which drop upon the floor during the course of a day's work and are swept up and thrown away when the

20 plant is cleaned. As a general rule, such metal articles include much that is usable, such as tacks, screws, nuts, bolts and the like so that when such waste continues for a considerable period of time, it is an appreciable

25 loss. Consequently it is the primary object of the invention to provide a machine which can be run over the floor of a factory or the like after the day's work and the major portion of the small waste metal articles

30 collected.

It is a further object to provide such a machine which will be electromagnetically actuated, whereby metal articles are segregated from other waste particles and collected so that they may be readily deposited in a suitable bin or other container.

35 Still another object is to provide a light, simply constructed and readily operated machine which can be easily propelled by a single operator.

40 With these and other objects and advantages in view, the invention resides in the novel features of construction, combination and arrangement of parts which will be hereinafter more particularly described and claimed.

In the accompanying drawing,

45 Figure 1 represents a substantially horizontal sectional view of the machine, which section is taken on the plane of the line 1—1 of Figure 3.

Figure 2 is a vertical transverse section on the plane of the line 2—2 of Figure 1.

50 Figure 3 is a front elevational view of the machine.

55 In this drawing I have illustrated but a

single embodiment of the invention which is in the nature of a wheeled collector adapted to be pushed about over the floor or ground from which the waste material is to 60 be collected. However, I may so modify the main features of the invention as to incorporate the same in a collector which can be otherwise used than by moving the same over the ground or floor. Consequently, it is 65 to be understood that it is within the scope of this invention to make various changes in the form and proportions of the different parts of the invention, without departing from the principles thereof or sacrificing 70 any of the obvious advantages.

Referring more particularly to the drawing, the reference character 1 denotes a suitable support which, in the present instance is in the nature of a casing or housing having a cover 2 and provided at its rear end adjacent its opposite sides with roller carrying brackets 3. In each of these brackets is journaled a supporting roller or wheel 4 whereby the rear end of the machine is movably supported on the floor surface. At the front end of the casing 1, or at any other suitable point thereon, is a floor surface engaging castor or roller 5. The method of attaching this roller 5 in the present embodiment consists in journaling same to a vertically slidable supporting plate 6 having a longitudinal slot 7 for the reception of a pair of bolts 8. It will be noticed that the bolts project from the front wall of the casing 1 and when nuts 9 are threaded thereon, the plate 6 is held in adjusted position against said casing.

Within the casing 1 I dispose a plurality of electromagnets 10, in the present instance four being shown, from which their cores 11 project and are extended through openings in the front wall of said casing after which they are bent downwardly and then laterally as at 12. In other words, the cores of the 100 magnets 10 have substantially right angular collecting members secured to their outer ends and the arms 12 of these members are parallel to and relatively close to the floor surface. Thus when the electro-magnets are 105 energized, the collecting arms 12 will attract various small particles and articles of metal.

Inasmuch as it is desirable that this machine be actuated by means of service electric current, a resistance coil 13 is also disposed in the casing 1 and the current is not only directed through the coils of the mag-

nets 10, but through this resistance coil 13, thereby securing a suitable reduction. The current circulates into and out of the casing 1 through current conducting wires 14, one 5 of which is connected with a snap switch 15.

The casing 1 is propelled by means of a handle 16, at one end of which is a yoke 17. From the several figures of the drawings, it will be seen that the ends of the arms of this 10 yoke 17 are journaled in sockets 18 on the opposite sides or ends of the casing 1. However, this or any other suitable means may be used for pivotally mounting the handle upon the casing. Also, if desired, the switch 15 15 can be mounted upon the handle 16 as indicated in Figure 1. When the machine is to be operated, the workman propels the casing over the floor surface, from which the articles are to be collected, by means of the 20 handle 16. After he has turned on the electric current and thus energized the electro-magnets 10 and the collecting arms 12 thereof, various metallic articles will be attracted to the latter and held thereon until said 25 magnets are deenergized by cutting off the current. In practice, the machine is moved over a designated area until a considerable quantity of metal has been collected on the

arms 12, whereupon it is propelled or carried to a suitable storage receptacle into which 30 the collected articles may be deposited. Although the arms 12 are normally placed in close proximity to the floor surface, this distance is readily varied as the result of the means of attaching the single forward sup- 35 porting roller 5.

I claim:

In a mechanism of the class described, a wheeled support, a housing carried thereby, a removable cover for said housing, a plurality of electro-magnets horizontally disposed within the housing with the cores thereof extending forwardly through the housing, then vertically downwardly and then laterally parallel to the surface over 45 which the device is to be moved, and means for vertically adjusting the forward end of the housing and thereby vertically adjusting the laterally extending portions of said cores. 50

In testimony that I claim the foregoing I have hereunto set my hand at Sheboygan, in the county of Sheboygan and State of Wisconsin.

WILLIAM NELESEN.
